8 Claims. (Cl. 66—153)

1

This invention relates to drawing-off mechanism for circular knitting machines adapted for knitting articles of hosiery in a continuous string, such machines being of the type in which the knitted material from a needle cylinder (which rotates for circular knitting and oscillates for oscillating knitting) passes between a pair of stepwise rotatable drawing-off rollers which are connected to the machine's driving mechanism for operation thereby.

In drawing-off mechanism hitherto used for circular knitting machines of the double cylinder type, the drawing-off rollers move circularly in unison with the needle cylinder and the knitted material—that is, they rotate bodily about the needle-cylinder axis—only during circular knitting, whilst during oscillating knitting, that is when knitting heels and toes, they remain in a stationary location. During the oscillation motion, in a known construction of such machines, the drive of the drawing-off rollers is interrupted in such a way that the drawing-off mechanism together with the usual fabric-protection drum are uncoupled from the drive of the oscillating needle cylinder.

An object of the present invention is to avoid the disadvantages of known drawing-off mechanisms by providing an auxiliary device which during oscillation of the needle cylinder can be set to impart stepwise rotation to the drawing-off rollers.

Another object of the invention is to provide drawing-off mechanism for circular knitting machines having for the driving of its drawing-off rollers an auxiliary actuating device which can be put into or out of action during the oscillatory motion of the needle cylinder, the auxiliary device acting in substitution for the then inactive main actuating device.

Another object of the invention is to provide drawing-off mechanism for a circular knitting machine of the type including a needle cylinder, gearing for oscillating said cylinder and drawing-off rollers as a unitary assembly about the cylinder axis, said mechanism to have a part moving to-and-fro with said gearing in timed relationship with said cylinder (this movement being additional to the oscillation), an auxiliary actuating device which is operatively connected to said rollers and is adapted to move to-and-fro with said part and to turn said rollers about their own axis when said device moves to-and-fro; and control mechanism which can be moved to engage said device and hold it at rest during the opera-

2

tion of said gearing and movement of said part therewith.

The auxiliary device according to the invention may comprise an arm adapted to be rocked about an axis spaced from the axis of movement of a pin provided conveniently on the knitting-machine's usual quadrant gear, namely a gear-toothed segment, such pin constituting the aforesaid part, and may be formed with a hooked end 10 engageable by said pin when said device moves to-and-fro in unison therewith, the arrangement being such that said pin forces said device to move additionally and transmit a turn to the drawing-off rollers. The hooked end and carrier 15 pin move or tend to move in divergent arcuate paths, the divergence defining the stroke of a pawl which is operated by said device to actuate ratchet-mechanism for turning the drawing-off rollers.

20 The drawing-off mechanism may include a lever controlled by the usual controlling drum of the knitting machine, and said lever may carry a spring-urged member having a slide-surface which is forced against a pin on the auxiliary 25 device, the arrangement being such that when the lever is turned by the controlling drum said member holds the device temporarily inoperative in its rest position.

An embodiment of the invention is illustrated by way of example in the drawings, in which:

30 Fig. 1 is an elevation of parts of a circular knitting machine including the drawing-off mechanism and an auxiliary device for operating it.

Fig. 2 is a side elevation corresponding to Fig. 1, being in the direction of the arrow II thereof.

35 Fig. 3 is a perspective view of a detail of Fig. 1.

Fig. 4 is a detail of Fig. 2, being drawn to a larger scale than Figs. 1 and 2.

The known drawing-off mechanism comprises 40 two drawing-off rollers 1, 2, which are borne by a support in the form of a bracket 3 and are spring-urged against each other. The rollers 1, 2 are turnable around their longitudinal axes 4, being mechanically inter-connected by the usual 45 pair of similar gearwheels, one only of which is shown, being indicated by 1A in Fig. 2. Thus, when the roller 1 is constrained to turn as hereinafter explained, the roller 2 will turn to the same extent, but in the opposite direction, so 50 that the rollers will draw the gripped knitted material 5 downwards. The usual material protection drum or receptacle 6 is provided below the rollers 1, 2 on the one drawing-off roller 1 there is fixed outside of the bracket 3 a ratchet 55 wheel 7, in which engages a pawl 8 on a two-

armed lever 9, which is fulcrummed under the ratchet wheel 7 on a pin 10 on the bracket 3. Between the pawl 8 and the pin 10 there is screwed to the lever 9 a pin 11 on which a holder 12 is pivotally mounted, being held in place by means of a cotter pin 13.

The pin 11 is provided as the usual support for a usual actuating roller (not shown) by means of which the main or normal device (also not shown) for actuating the drawing-off rollers is operated during the manufacture of regular hosiery material by circular knitting. For such knitting, the holder 12 is removed and replaced by the said roller, as hereinafter explained.

In the end of the holder 12 there is adjustably screwed a pull-rod 14 with a hook shaped bent end 15. The holder 12 and rod 14 constitute a pivotal-arm device, which can swing around the pivot pin 11, the end 15 tending to follow an arcuate path I. The pull-rod is secured to the holder by means of a lock-nut 16 against unscrewing. A tension spring 17, which is connected at one end to an arm of the lever 9 and at the other end to the bracket 3, has the task of urging downwards the longer arm of the lever 9 so far that it abuts against a camlike incline 18. The pawl 8 is connected by means of a tension spring with a detent 20 which is pivotally mounted on the side wall of the bracket 3 and prevents turning back of the drawing-off roller 1.

A pinion 26 is journaled on the main shaft 25 but can be coupled thereto. This pinion meshes with the teeth of the usual toothed segment or so-called quadrant gear 21, which is oscillated constantly during the operation of the machine by the usual rotary transmission shaft (not shown), a gear-wheel 22 thereon and a connecting-rod 23, which links a crank-pin 22A on the wheel 22 to a pin 22B on the body of the segment 21. The journal or axle 24 of the segment 21 is borne by the machine frame 24A (Fig. 4). It is through the pinion 26, the main shaft 25 and intermeshing bevel wheels 27, 28 that the needle cylinder 29 of the knitting machine receives its oscillating motion. The journal 24 is adjustable in relation to the pin 11 of the holder 12. An actuating part in the form of a carrier pin 30 arranged on one side of the toothed segment 21 moves around the journal 24 in an arcuate path II, which crosses the arcuate path I of the hooked end 15. The distance x between the two paths defines the stroke of the means for driving the drawing-off rollers 1, 2. The holder 12, under the pull of a spring 31 connected at one end to it, holds the pull-rod 14 against the carrier pin 30, the spring 31 being anchored at its other end to the lever 9.

The machine has control mechanism for starting and stopping the operation of the drawing-off rollers 1, 2 during oscillating knitting. This mechanism includes a pin 32 at the upper end of the holder 12 of the pivotal-arm device. This mechanism also includes, to cooperate with the pin 32, a bellcrank lever 33, a controlling drum 34 and a locking part 35 fastened thereon. One arm 36 of the bellcrank lever 33, which is journaled on the frame 24A, slidably engages at its end 37 either on the locking part 35 or on the upper surface of the controlling drum 34. In the other arm 38 of the lever 33 a pin 39 is fixed on which a carrier 40 is pivotally mounted. A member 42 adjustably connected by screws 41 to the carrier 40 is provided with two slide surfaces 43 and 44 and is pulled by a spring 45 towards a pin 46 projecting from the lever arm 38. The

tension spring 45, which is connected on the one hand to the pin 46 on the lever arm 38 and on the other hand to the member 42, forces the slide surface 44 of the member 42 against the pin 32 of the holder 12 (see Fig. 1) whereby the holder 12 is held in the rest position A. Thus, the pull-rod 14 of the pivotal-arm device is held stationary, and free from the influence of the pin 30.

A complete motion of the carrier pin 30 from the rest position A to the opposite limit position B corresponds to a revolution of the needle cylinder 29 or to the knitting of a row of stitches which is pulled forward by the auxiliary device 12, 14, 15 when the locking part 35 is inactive. The return motion of the carrier pin 30 corresponds again to a revolution of the needle cylinder 29 in the reverse direction or the knitting of a further row of stitches, which is not pulled forward. From this it is obvious that a forward-pulling action occurs every second row.

The machine includes means, hitherto usual in double-cylinder seamless-hose machines, for rotating the bracket 3, the drawing-off rollers 1, 2 and associated parts and the knitted-material drum 6, all as a unitary assembly in unison with the needle cylinder 29. The means shown in Figs. 1 and 2 comprise a two-part side shaft 47, 48 journaled in the stationary frame 24A, intermeshing gearwheels 49 and 50 on the needle cylinder 29 and part-shaft 47 respectively, intermeshing gearwheels 51 and 52 on the part-shaft 48 and bracket 3 respectively, a clutch element 53 fixed to the part-shaft 47, a mating clutch element 54 slidable on the part-shaft 48 under or against the pressure of a spring 55, and a hand-operable fork 56 for operating the clutch element 54. The arrangement is such that when the clutch 53, 54 is closed, the bracket 3 rotates in synchronism with the cylinder 29; but, when the clutch is open, the bracket 3 remains at rest. Any appropriate means are provided for locking the bracket 3 when at rest in its proper location in relation to the frame 24A and other parts of the machine. As shown in Figs. 1 and 2, the machine has such means in the form of a withdrawable locking pin 57 screwed through a stationary gear case 58 which supports the stationary inclined member 18, the pin 57 being engageable with a locking hole provided for it in the gear wheel 52.

The operation of the drawing-off mechanism is as follows:

During the manufacture of regular hosiery material by circular knitting, the usual main actuating device (not shown in the drawings) is operative and the auxiliary actuating device forming the subject of the present invention is inoperative. For this way of operating the machine, the holder 12 with the rod 14 incorporated in the auxiliary actuating device is detached from the pin 11, which carries instead the usual actuating roller (not shown) constituting the main actuating device. The spring 31 is then also detached. The locking pin 57 is withdrawn, and the clutch 53, 54 is closed. Thus, the knitting cylinder 29 continuously rotates, as is necessary in circular knitting, and the bracket 3 rotates with it; and the bracket carries with it the drawing-off rollers 1, 2 and the associated mechanism 7 to 11. The inclined member 18 however remains stationary, and therefore acts in the usual well-known way as a cam on the said actuating roller, thus rocking the pawl-lever 9 and stepping

round the ratchet-wheel 7 and the drawing-off rollers 1, 2.

For oscillating knitting, that is for the knitting of stocking feet, the previously mentioned actuating roller is detached from the pin 11 and in its place there is attached the holder 12 of the auxiliary actuating mechanism. The clutch 53, 54 is opened and the locking pin 57 is inserted. In operation, the knitting cylinder is oscillated by the toothed segment 21 and gearwheels 26, 27 and 28, but the bracket 3 and the fabric-protection drum 6 and the mechanism 7 to 11 all remain stationary, with the result that the inclined member 18 is inoperative.

In the knitting of the heel *a* or toe *b* of a stocking foot, the end 37 of the bellcrank lever 33 bears upon the locking part 35 of the controlling drum 34, as Fig. 1 shows so that the slide-surface 44 of the member 42 presses against the pin 32 under the pull of the spring 45, and the holder 12 is held in the rest position A. The hook-shaped end 15 of the pull-rod 14 is at that time above the actuating part constituted by the carrier pin 30, so that the latter can freely swing out of the rest position A into the active position B and back again.

After the finish of the knitting of a heel or toe and following the turning of the controlling drum 34, the end 37 of the bellcrank lever 33 slides from the locking part 35 so that the slide-surface 44 of the member 42 releases the pin of the holder 12. The spring 31 connected to the holder 12 causes the holder 12 and the hook-ended pull-rod 14 to follow the motion of the carrier pin 30 from A to B. As the pin 30 moves in the arcuate path II, the radius of which is smaller than the radius of the circular path I, the pin after leaving its rest position A gradually reaches the hook-shaped end until it fully engages this. The carrier pin 30, on its further motion and before reaching the opposite limit position B, lifts the hook-shaped end 15 the maximum distance *x*; so that the holder 12, overcoming the resistance of the spring 17, turns the lever 9 upwards about the fulcrum pin 10 and the pawl 8 turns the ratchet-wheel 7 and so the formerly stationary drawing-off roller 1 is constrained by the action of the pin 30 to rotate a step around its longitudinal axis 4. This rotational motion is transmitted to the other drawing-off roller 2, so that the knitted material, turning to-and-fro with the needle cylinder 29 and gripped between the rollers 1 and 2, is pulled downwards into the material protection drum 6.

On the return of the carrier pin 30 from B to A the hook-shaped end 15 remains engaged with the carrier pin 30 under the pull of the spring 17, so that the pull-rod 14 sinks with the holder 12 and lever 9 and the pawl 8 slides idly over the teeth of the ratchet-wheel 7 within pulling the material forward. As soon as the position A is reached the grip between the carrier pin 30 and the hook 15 is loosened, and the tension spring 31 holds the pull-rod 14 against the carrier pin 30 until the motion from A to B recurs.

Before the beginning of the knitting of a heel *a* or toe *b*, on rotation of the controlling drum 34 the end 37 of the bellcrank lever 33 slides upon the locking part 35, so that the arm 38 of the lever 33 moves downwards and one of the two slide-surfaces 43, 44 bears upon the backwards and forwards swinging pin 32 of the holder 12. If for example the holder 12 or its pin 32 is performing the return motion from B to A, the pin 32 by the lifting of the spring-loaded member

42 passes under the forward slide-surface 43 and reaches the rear slide-surface 44 which holds the pin 32 fast in the rest position. The pulling-forward action of the auxiliary device is thereby interrupted. Thereafter the carrier pin 30 of the toothed segment 21 can perform unhindered its swinging motion until after the knitting of a heel or toe it again engages the hook-shaped end 15 in order to draw the material forward again.

By adjusting the hook-ended rod 14 in the holder 12, the divergence *x* between the arcuate paths I and II can be regulated, thus regulating the stroke of the pawl 8 on the ratchet-wheel 7 and the extent of each rotational movement of the drawing-off rollers 1, 2. Thus the drawing-off action can be regulated to suit the length of the knitted stitches.

The subject of the invention as illustrated by the drawings and explained by the foregoing description is not to be considered as confined to the described embodiment, which can be altered without departing from the spirit of the invention.

For instance, it is not essential that the carrier pin 30 must be on the toothed segment 21; it could be on the journal 24 so as to swing to and fro in unison with said segment.

I claim:

1. Drawing-off mechanism for circular knitting machines of the type including a needle cylinder capable of both rotary and oscillating knitting, gearing including an oscillating gear member for oscillating said cylinder, drawing-off rollers for the knitted material, a rotatable support for said rollers, and means for locking said support against rotation and holding the support in a stationary location during oscillation of said cylinder; said mechanism comprising an actuating part connected to said gear member to move to-and-fro therewith in timed relation with oscillations transmitted thereby to the needle cylinder, a device used only during oscillating knitting, said device being mounted to move to-and-fro with said actuating part, an operating connection between said device and the drawing-off rollers for rotating said rollers stepwise when said device moves to-and-fro, and control mechanism for stopping the operation of said rollers by said device, which mechanism is movable to engage said device and hold it inoperative whilst said gearing is in operation during oscillating knitting.

2. Drawing-off mechanism for circular knitting machines of the type including a needle cylinder capable of both rotary and oscillating knitting, gearing including an oscillating gear-toothed segment for oscillating said cylinder, drawing-off rollers for the knitted material, a rotatable support for said rollers, and means for locking said support against rotation and holding the support in a stationary location during oscillation of said cylinder; said mechanism comprising an actuating pin on the gear-toothed segment, said pin moving to-and-fro with said segment, a pivotal-arm device used only during oscillating knitting, said device being mounted to engage and move to-and-fro with said pin, an operating connection between said device and the drawing-off rollers for rotating said rollers stepwise when said device moves to-and-fro, and control mechanism for stopping the operation of said rollers by said device, which mechanism is movable to engage said device and hold it sta-

60
65
70
75

tionarily free from said pin whilst said segment is in operation.

3. Drawing-off mechanism for circular knitting machines of the type including a needle cylinder capable of both rotary and oscillating knitting, gearing including an oscillating gear member for oscillating said cylinder, drawing-off rollers for the knitted material, a rotatable support for said rollers, and means for locating said support against rotation and holding the support in a stationary location during oscillation of said cylinder; said mechanism comprising a lever device used only during oscillating knitting, said device being pivotally mounted to swing to-and-fro with said gear member, an operating connection between said device and the drawing-off rollers for rotating said rollers stepwise when said device swings to-and-fro, and control mechanism for stopping the operation of said rollers by said device, which mechanism is movable to engage said device and hold it inoperative whilst said gearing is in operation during oscillatory knitting.

4. Drawing-off mechanism for circular knitting machines of the type including a needle cylinder capable of both rotary and oscillating knitting, gearing including a gear-toothed segment that oscillates about an axis to operate said cylinder, drawing-off rollers for the knitted material, a rotatable support for said rollers, and means for locating said support against rotation and holding the support in a stationary location during oscillation of said cylinder; said mechanism comprising an actuating pin on the gear-toothed segment, an arm used only during oscillating knitting, said arm being pivotally connected to a pawl-lever, the axis of pivotal connection of said arm being spaced from said segment's axis, a hook formation on said arm for engagement by said pin, means urging said arm to maintain engagement with said pin and swing in unison with said segment, said hook formation tending to describe an arcuate path diverging from an arcuate path described by said pin, a ratchet-mechanism for driving the drawing-off rollers, being operated by said pawl-lever in the swinging of said arm, and control mechanism for stopping the operation of said rollers by said device, which mechanism is movable to engage said arm and hold it inoperative whilst said gearing is in operation during oscillatory knitting.

5. Drawing-off mechanism as claimed by claim 4 in which the arm pivotally connected to the pawl-lever comprises parts that are lengthwise adjustable for regulating the stroke of the pawl-lever.

6. Drawing-off mechanism for circular knit-

ting machines of the type including a needle cylinder capable of both rotary and oscillating knitting, gearing including an oscillating gear member for oscillating said cylinder, drawing-off rollers for the knitted material, a rotatable support for said rollers, and means for locating said support against rotation and holding the support in a stationary location during oscillation of said cylinder; said mechanism comprising a device mounted to move to-and-fro with said gear member, a driving connection used only during oscillating knitting, said connection being interposed between said device and the drawing-off rollers for rotating said rollers stepwise when said device moves to-and-fro, and control mechanism for rendering said device either operative or inoperative, said control mechanism including a lever movable into one or other or two positions, and a spring-urged member on said lever for engaging said device in one of said positions and holding the device against movement with said gearing.

7. Drawing-off mechanism as claimed by claim 6 in which said device has a projection and said spring-urged member has slide-surfaces for engaging said projection in movement of the device into inoperative position and for holding the device in that position.

8. Drawing-off mechanism for circular knitting machines of the type including a needle cylinder capable of both rotary and oscillatory knitting, gearing for oscillating said cylinder, drawing-off rollers for the knitted material, a rotatable support for said rollers, means for locking said support against rotation and holding the support in a stationary location during oscillation of said cylinder and a mechanism for operating said rollers; said operating mechanism including an auxiliary actuating device used only during oscillating knitting, means moving with said gearing and acting on said device to actuate said operating mechanism, and control means acting on said device to render said operating mechanism either operative or inoperative whilst said cylinder-oscillating gearing is in operation during oscillatory knitting.
